CISCO, CALIFORNIA, A CORPORATION OF CALIFORNIA.

PROCESS FOR CLARIFYING AND IMPROVING THE COLOR OF PETROLEUM OILS.

1,404,374.

Specification of Letters Patent. Patented Jan. 24 1922.

Application filed February 18, 1920. Serial No. 359,755.

To all whom it may concern:

Be it known that we, MARVIN L. CHAPPELL and MERLE M. MOORE, citizens of the United States, residing at El Segundo, in 5 the county of Los Angeles and State of California, have invented a new and useful Process for Clarifying and Improving the Color of Petroleum Oils, of which the following is a specification.

This invention relates to the art of clarifying and improving the color of petroleum oils by the use of clarifying and decolorizing agents. While not necessarily limited thereto, it more specifically refers to the 15 art of clarifying and improving the color of lubricating oils.

One object of the invention is to provide a method or process whereby a substantially uniform clarified oil of the desired color 20 may be produced with a minimum consumption of the clarifying decolorizing agent; another object is to provide such a process which may be performed with a minimum consumption of time.

25 An object of the invention is to provide a method whereby hydrocarbon oil may be mixed with a clarifying and decolorizing agent and quickly heated to a temperature of 250° F., or higher, thoroughly com- mingled and cooled before any substantially 30 oxidizing action can take place.

An object of the invention is to provide a method whereby a more finely comminuted decolorizing and clarifying agent may 35 be used to clarify and decolorize a petroleum hydrocarbon oil than has heretofore been used.

An object of the invention is to provide a process, for the purpose specified, where- 40 by the oil to be treated and the clarifying and decolorizing agent may be thoroughly intermingled, in any suitable manner, and not depend upon percolation of the oil through the agent.

45 An object of the invention is to provide a method or process whereby the treated oil may be quickly cooled and filtered without loss in color or the formation of oxidized products.

50 The extraction of coloring matter from petroleum oils is generally understood to be an adsorbing process, dependent upon time of contact, temperature and surface exposed. For example, for a given quantity

and weight the finer the comminution of 55 the decolorizing agent, the more surface thereof will be exposed to the oil and the more coloring matter will be condensed or adsorbed upon the surface of the decolorizing agent. We have found that a decolorizing agent, ground so that approximately 60 97% will pass through a 200 mesh sieve or screen, gives the more satisfactory results for our process or method.

Heretofore by usual methods it has been 65 customary to clarify and improve the color of hydrocarbon oils and particularly lubricating oils by percolating such oil through long pipes or other forms of containers filled with a decolorizing and clarifying 70 agent, such decolorizing and clarifying agent comminuted or finely divided so it will pass through a No. 30 standard mesh sieve but will be retained on a No. 60 mesh standard sieve; also when fuller's earth 75 is used for the more viscous oils, the same has been used of such comminution as to pass through a 15 to 30 mesh sieve. In such processes the oil is usually retained at substantially 130° F. These methods 80 have been found very slow and usually require from 5 to 7 days before the oil percolates through the filtering bed thus formed. Not only have these methods used been found to be slow but they also require 85 the use of very large quantities of decolorizing agent. With such methods as heretofore practiced it has been noted that the viscosity of the treated oil has been sub- 90 substantially lowered.

With our process as hereinafter described and explained we require only approxi- 95 mately 2 hours for the entire treatment of the oil for the purpose of decolorization and clarification and at the same time retain the oil with a greater viscosity than where the usual methods or processes are used, and also are enabled to perform the clarification and decolorization with a minimum consumption of decolorizing and clarifying 100 agent.

By our process also we obtain a superior product and substantially free from oxidized products.

By our process in its preferred form, we 105 mix the clarifying agent directly with the oil, and do not depend upon mere percolation of the oil through such agent.

In the preferred embodiment of our invention our method or process in clarifying or improving the color of hydrocarbon oil, consists either in batch treatments or by 5 continuous methods whereby hydrocarbon petroleum or lubricating oil is quickly heated to 250° F. or higher by suitable heating devices, while such oil is commingled with a clarifying and decolorizing agent in 10 a finely comminuted or pulverized condition and in such quantities as is necessary to obtain the desired color and grade; continuing the commingling or agitating of such hydrocarbon oil and decolorizing agent for 15 such a period of time and at such a temperature as is necessary to obtain the desired extraction of color from such oil; then immediately partially cooling said oil and separating therefrom the decolorizing agent 20 and adsorbed matter, by suitable means; and finally cooling said oil to the desired temperature.

More specifically our invention provides a process whereby hydrocarbon oil may be 25 heated quickly to a desired temperature (substantially 250° F. or above) by rapid circulation through heated pipe coils or tubes or in any suitable vessel or chamber, without any part of said oil being heated 30 beyond the desired temperature; thoroughly commingling the heated oil and decolorizing and clarifying agent; quickly partially cooling the same below oxidizing temperature so as to minimize the oxidation; separating the adsorbed decolorizing and clarifying agent and coloring matter from the oil; and then cooling the oil to the desired 35 temperature.

The preferred embodiment of our invention 40 will be more readily understood by reference to the accompanying drawings, illustrating a form of apparatus by which the same may be performed. The drawing is a diagrammatical form of an apparatus by 45 which such preferred embodiment of our invention may be performed.

In the drawings 2 represents a storage tank for the oil to be treated. This tank 2 is connected by a pipe 3 with a treating 50 tank 4. The tank 4 may be entirely open at its top or may be closed by a dome 5 as indicated in the drawings and provided with a vapor outlet 6. The treating tank 4 is connected by means of a pipe 7 to a pump 55 8 which discharges through a pipe 9 connected through a valve 10 to a heater 11 and through a valve 12 to a cooler 13. The heater 11 may be of any suitable form of construction but we prefer to use a Braun 60 heater which is a heater composed of small pipes enclosed in a shell so that the heating medium fills the shell and surrounds the pipes through which the oil is conducted, thus affording a quick means of raising 65 the temperature of the oil as it passes

through the pipes or tubes of the heater. This heater 11 is connected by means of a pipe 14 to the treating tank 4. As shown in the drawings the heater 11 is also connected by a pipe 15 to the pump 8. 16 represents a valve in the pipe or line 15 and 17 represents a valve in the pipe or line 7. 18 represents a storage and feeder bin or hopper in which the finely comminuted clarifying or decolorizing agent is provided. From this bin 18 such agent may be introduced into the treating tank 4 in the desired quantities, such quantities being regulated by means of a suitable slide or valve 19. 13 represents a cooler which is connected to receiver 21 by a suitable pipe 22. The receiver 21 may be connected to a pump 23 by pipe 24. The pump 23 discharges through a pipe 25 which in turn is connected to a filter press, device or chamber 26 of any ordinary or preferred construction. 27 represents a receiving pan to hold the spent clarifying and decolorizing agent. 28 represents a conveyor to convey the spent clarifying and decolorizing 90 agent to storage or for recovery.

The filtering device or press 26 is connected to a cooler 29 by a suitable pipe 30 and in turn the cooler 29 is suitably connected to a storage vessel 31 as by a pipe 32. 95 33 indicates a pipe which leads from the storage vessel 31 to any other suitable place or means of storage. When the apparatus is in the form shown in the drawing the preferred embodiment of our process is performed as follows:

The treating tank 4 is first filled with the predetermined amount of hydrocarbon oil to be treated, such oil being drawn through the pipe 3 from the storage tank 2. Decolorizing and clarifying agent in the required amount is then added by suitable operation of the valve 19. This decolorizing agent is thoroughly commingled with the oil by any suitable means, such for instance, as circulation by means of the pump 8 through the heater 11 and back into the tank 4. This circulation is continued until the commingled decolorizing agent and oil is raised to a temperature of approximately 115 250° F., depending upon the oil to be treated. After the commingled oil and agent have thus been raised to the desired temperature, they are subjected to this temperature for a predetermined period, which with certain oils does not exceed 5 minutes. By thus quickly raising the temperature of the commingled oil and decolorizing agent and circulating the same through a suitable heating device, we are enabled to subject the commingled oil and agent to the critical temperature for the desired length of time without subjecting any portion of the oil to a greater temperature than desired, thus minimizing the oxidation which would be pro- 120 125 130

moted by too high a temperature and eliminating the danger of any portion of the oil approaching decomposing temperature.

After thus being subjected to the critical 5 temperature for the desired length of time the commingled oil and agent are immediately passed through a suitable cooler, such as the cooler 13 indicated in the drawings. In this cooler the temperature of the commingled oil and agent is reduced below the 10 temperature of rapid oxidation and discharged into a suitable receiver 21 from which they are drawn by the pump 23 and discharged through the filtering press or 15 apparatus 26, where the clarifying agent with the adsorbed coloring matter is separated from the oil and discharged and the clarified and decolorized oil is discharged into the cooler 29 from which cooler such 20 oil may be passed to any suitable storage vessel such as the storage vessel 31.

The passage of the commingled oil and agent through the heater 11 gradually but very quickly heats the commingled oil and 25 agent to the desired temperature without heating any material quantity of the oil beyond this temperature.

The passage of the treated hydrocarbon oil through the cooler 13 rapidly cools said 30 oil to a temperature at which no material oxidation or material lowering in the color of the oil will occur upon standing. This temperature is regulated to conform to the filtering rate of the oil. We prefer to maintain 35 a slightly higher temperature during the filtration of oils which are of a heavy viscosity.

While we prefer to use a filter press as the means of separating the clarifying and 40 decolorizing agent from the oil, our process is not necessarily limited thereto as we may use any suitable filtering means, centrifugal machine or other mechanical device by means of which the oil is obtained substantially 45 free from the spent clarifying and decolorizing agent.

As a clarifying and decolorizing agent we may use animal char, bone ash, fullers' earth, certain clays which have been treated with 50 acid, such as the clays from the well-known Death Valley, California, deposits, with adsorbent qualities, or any other or preferred material suitable therefor, and which will clarify and improve the color of the oil.

55 In utilizing our process for clarifying and decolorizing certain lubricating oils derived from California crude oils, we have found that by quickly raising the temperature of the commingled oil and decolorizing agent to approximately 300° F. and maintaining same at such temperature for approximately 5 minutes and then quickly cooling the same to approximately 150°, we secure the best results. It is obvious,

therefore, that our process is not limited 65 specifically to a particular temperature, the range of temperature to which the commingled oil and agent shall be subjected being from substantially 250° F. to the heat or 70 temperature at which the peak of the reaction takes place. Best results are secured by the higher temperatures so long as the temperature of the commingled oil and agent is retained below the temperature of the 75 peak of reaction.

We claim:

1. The process of clarifying and improving the color of a hydrocarbon petroleum oil which consists in commingling with the oil a clarifying and decolorizing agent 80 comminuted so that substantially 97% of such agent will pass through a 200 mesh sieve or screen, quickly raising the commingled oil and agent to a temperature not substantially less than 250° F. and below 85 the peak of the decolorizing reaction, maintaining such temperature until the reaction is effected, immediately cooling such oil and agent below the temperature of rapid oxidation, and separating the oil and agent 90 with its adsorbed coloring matter.

2. The process of clarifying and improving the color of a hydrocarbon petroleum oil which consists in quickly raising such oil commingled with a finely divided clarifying and decolorizing agent to a temperature not substantially less than 250° F. and below 95 the decolorizing point of chemical reaction, maintaining such heat during the period of such reaction, immediately partially cooling the intermingled oil and agent 100 below the temperature of rapid oxidation, and separating the oil and agent with its adsorbed coloring matter.

3. The process of clarifying and improving the color of a hydrocarbon petroleum oil which consists in commingling such oil with a clarifying and decolorizing agent comminuted so that approximately substantially 105 97% of such agent will pass through 110 a 200 mesh sieve or screen, quickly raising the commingled oil and agent to the temperature of the desired decolorizing reaction, maintaining such temperature to effect such reaction, immediately cooling the intermingled oil and agent to such a temperature 115 as to prevent rapid oxidation, and separating the agent and adsorbed coloring matter from the oil.

4. The process of clarifying and improving the color of hydrocarbon petroleum oil which consists in rapidly raising a commingled hydrocarbon oil and a clarifying and decolorizing agent to the temperature of the desired decolorizing reaction, maintaining such temperature to effect such reaction, immediately cooling the intermingled oil and agent to such a temperature as to 125

prevent rapid oxidation, and separating the agent and adsorbed coloring matter from the oil.

5. The process of clarifying and improving the color of a hydrocarbon petroleum oil which consists in quickly raising such oil commingled with a finely divided clarifying and decolorizing agent to the temperature of the desired decolorizing reaction, 10 maintaining such temperature to effect said reaction, immediately cooling such oil and agent below the temperature of rapid oxidation, and separating the oil and agent with its adsorbed coloring matter.
- 15 6. The process of clarifying and improving the color of a hydrocarbon oil which consists in rapidly circulating through a heating chamber the oil intimately commingled with a finely comminuted clarifying and 20 decolorizing agent to cause the reaction of said oil and agent, immediately cooling the

same to substantially prevent oxidation, and separating the oil from the agent and its adsorbed matter.

7. The process of clarifying and decolorizing a hydrocarbon oil which consists in commingling the oil with a decolorizing agent, quickly heating the same to approximately 300° F., substantially maintaining the same at substantially said temperature 25 to effect the reaction of said oil and agent, immediately cooling the same below the temperature of rapid oxidation; and separating the oil from the agent and its adsorbed matter. 30
